UNITED STATES PATENT OFFICE.

STEPHEN WILLIAM DUNN, OF MILWAUKEE, WISCONSIN.

AUXILIARY TOILET-SEAT.

1,194,972

Specification of Letters Patent. Patented Aug. 15, 1916.

Application filed July 7, 1914. Serial No. 849,540.

To all whom it may concern:

Be it known that I, STEPHEN W. DUNN, a citizen of the United States, residing at Milwaukee, in the county of Milwaukee, State of Wisconsin, have invented certain new and useful Improvements in Auxiliary Toilet-Seats; and I do hereby declare the following to be a full, clear, and exact description of the invention, such as will enable others skilled in the art to which it applies to make and use the same.

This invention relates to improvements in attachments for toilet seats.

The principal object of the invention is to provide an auxiliary seat for attachment to the customary closet seat which is particularly adapted for traveling purposes and particularly for children's use.

Another object is to provide a device of this character which can be conveniently carried in a handbag or satchel and which can be quickly and easily applied to or removed from the closet seat.

A still further object is to provide a device of this character which is so constructed and arranged that it can be left on the seat without interference of the opening and closing of the lid.

Other objects and advantages will be apparent from the following description, when taken in connection with the accompanying drawings.

In the drawings: Figure 1 is a plan view of a closet seat showing my attachment in position thereon. Fig. 2 is a vertical central longitudinal sectional view through Fig. 1.

Referring particularly to the accompanying drawings, 10 represents the ordinary closet seat having the usual central opening 11 in which my auxiliary seat is adapted for use. The auxiliary seat comprises a

ring 12 slightly elongated and of practically the same design and shape as the main seat. Secured to the underside of the forward end 45 of the ring 12 is a wire yoke 13, the forward portion of which is bent downwardly and inwardly as indicated at 14 and is covered with the rubber tubing 15. This curved portion of the yoke is adapted to embrace 50 the forward edge portion of the main seat 10. Extending in divergent relation from the rear portion of the auxiliary seat ring 12 are arms 16, each of which is covered with the rubber tubing 17. The ring 12, 55 when properly placed, will be disposed approximately centrally in the opening of the main seat and is disposed far enough down in the opening to permit the cover of the seat to be closed without interference of the 60 auxiliary device. It will be noted that the rubber buttons 18 of the cover will support the cover which is out of engagement with the auxiliary seat.

What is claimed is:

An auxiliary seat for a toilet seat comprising a seat ring, of a size and shape to fit within the opening of the toilet seat, a forwardly extending and downwardly and inwardly curved yoke member secured to the forward end of the ring for embracing engagement with the forward portion of the main seat, and a horizontally disposed and rearwardly extending yoke carried by the rear portion of the auxiliary seat ring for supporting engagement on the rear portion of the toilet seat.

In testimony whereof I affix my signature in the presence of two witnesses.

STEPHEN WILLIAM DUNN.
